UNITED STATES PATENT OFFICE.

PETER D. LA FAYETTE, SR., OF COLLINSVILLE, ASSIGNOR OF ONE-HALF TO
PETER D. LA FAYETTE, JR., OF MIDDLETOWN, CONNECTICUT.

WINDOW.

SPECIFICATION forming part of Letters Patent No. 373,238, dated November 15, 1887.

Application filed March 23, 1887. Serial No. 232,061. (No model.)

To all whom it may concern:

Be it known that I, PETER D. LA FAYETTE, Sr., of Collinsville, in the county of Hartford and State of Connecticut, have invented a certain new and useful Improvement pertaining to Windows, of which the following is a description, reference being had to the accompanying figures of drawings, wherein—

Figure 1 is a front view of a window-casing and the upper and lower window-sashes embodying my improvement. Fig. 2 is a view of the meeting-rails of the two sashes in cross-section on plane $x\ x$. Fig. 3 is a detail view showing the outer side of the upper rail of the lower sash. Fig. 4 is a view in cross section on plane $y\ y$. Fig. 5 is a view in cross-section on plane $z\ z$. Fig. 6 is a view in section of the meeting-rails of the two sashes, showing the depth of the recess in which the blade is hidden.

My invention relates to the class of windows in which the sashes slide vertically past each other in raising and lowering; and the object of my improvement is to provide a device 25 that is cheap, simple, and efficient for fastening the sashes closed, and at the same time prevent the entrance of dust and air between the meeting-rails of the sashes.

My improvement consists in a vertically-moving sash having a socket in which is seated a blade that is provided with handles for pushing out the blade or drawing it into the socket, the shanks of the handles being so attached to the blade as to form runners upon which 35 the blade slides and by which it is guided, in combination with a vertically-moving sash having a socket to receive the blade when it is projected from the lower sash, as more particularly hereinafter described, and pointed 40 out in the claim.

In the accompanying drawings the letters $a\ b\ c\ d$ denote the window-casing as a whole.

The letters $e\ f\ g\ h$ denote the upper sash as a whole.

The letters $i\ j\ k\ l$ denote the lower sash as a whole. The upper rail, i , of the lower sash carries in it a metallic blade, m , which can be moved back and forth transversely of the sash by means of the handles n . The shanks of the 45 handles are rounded on the lower side, (see Fig. 2,) and are rigidly attached to the blade

in such a manner that the rounded surface projects below the blade into a transverse socket cut for it. By this construction runners are provided which slide in ways and 55 guide the blade when moved in or out. This of course reduces the friction and prevents the blade from becoming jammed in the recess. This blade extends entirely across the window-opening, and it can be made to lie wholly 60 within the sash-rail i or made to project therefrom and enter into the groove o in the lower rail, g , of the upper sash. When this blade m is entirely within the rail i , it does not interfere with the up and down movement of 65 either sash; but when it is made to project into the groove o it not only prevents either sash from being moved, but it acts as a dust and air excluder.

Both sashes have a groove, p , in the sides 70 and ends, and the sides and ends of the interior of the window-casing are provided with corresponding projecting rails, r . The side rails serve as ways on which the sashes move, and the rails at both the sides and ends act as 75 dust and air excluders.

I am aware that window-sashes have been provided with blades or strips of metal or other material which serve as fasteners and weather-strips, such being shown in United 80 States patents to G. M. Evans, No. 219,809, and D. Coulon, No. 85,729, and these I do not broadly claim.

I claim as my improvement—

The combination of the vertically-moving 85 sashes, having longitudinal recesses in their meeting-rails, and the transversely-moving blade hidden in the recess in the lower sash, the said blade having handles rigidly attached thereto, the shanks of which handles project 90 below the blade into transverse grooves in the sash, which form ways to support and guide the device in its movement, substantially as described.
